UNITED STATES PATENT OFFICE.

LEROY R. BOWLES, OF HOLLYWOOD, CALIFORNIA, ASSIGNOR, BY DIRECT AND MESNE ASSIGNMENTS, OF ONE-THIRD TO PERCY B. McCABE AND TWO-THIRDS TO HENRY S. CAHN AND B. C. McCABE, ALL OF LOS ANGELES, CALIFORNIA.

EVEN-HEAT ELECTRIC IRON.

Application filed December 8, 1921. Serial No. 520,875

To all whom it may concern:

Be it known that I, LEROY R. BOWLES, a citizen of the United States, residing at Hollywood, in the county of Los Angeles 5 and State of California, have invented a new and useful Improvement in Even-Heat Electric Irons, of which the following is a specification.

An object of this invention is to provide 10 an even heat electric iron of simple and satisfactory construction in which the current controlling device is mounted external to the smoothing iron proper, but close enough thereto to be controlled by the changes of 15 temperature of the iron without being subjected to the high temperature thereof, and an object is to so construct and arrange the appliance that it can be accurately adjusted to deliver the current as required for a pre- 20 determined temperature of the iron.

An object is to provide a simple and convenient arrangement for adjusting such spring and for holding it in the desired adjustment.

25 The invention is applicable in various forms and may be constructed with and also without platinum contact points.

Objects are durability of parts and sensitivity of operation.

30 Other objects, advantages and features of invention may appear from the accompanying drawing, the subjoined detail description and the appended claims.

The accompanying drawing illustrates the 35 invention.

Figure 1 is a broken perspective view of a smoothing iron constructed in accordance with this invention.

Fig. 2 is a plan section of the same taken 40 directly above the electrical resistance.

Fig. 3 is an enlarged horizontal section on line indicated at w^3 , Fig. 4.

Fig. 4 is a section on line w^4 , Figs. 2 and 3 on the scale of Figs. 1 and 2.

45 Fig. 5 is a fragmental section illustrating the connection between the handle, the housing and the body of the iron.

Fig. 6 is a longitudinal section on a reduced scale of the housing detached.

50 The smoothing-iron body 1 may be of any suitable construction provided with electrical resistance 2 by which it is to be heated.

The housing 3 fits upon the body 1, and is detachably secured thereto by nuts 4, 5, which screw upon stud screws 6 that are inserted through the heat retaining casting a and screwed into the body 1; said nuts 4, 5 hold the handle 7 and the housing 3 in place on said smoothing-iron body. The housing 3 is provided with a rearward extension 8 55 forming an insulating air chamber 9 rearwardly of the smoothing-iron body, and said housing terminates in a rearwardly projecting case 10 having a floor 11 slightly above the bottom 12 of the smoothing iron. 60

Said case 10 is adapted to contain the insulating block 13 which is inserted thereinto while the housing is detached; said block rests upon the floor 11 and is provided with holes 14, 15 and 16. Said block may be made 70 of fiber or any other suitable insulating material, and is provided with a seat 17 for a nut 18 to receive a screw 19, which is inserted through the hole 14 and through the block and is screwed into said nut to hold the block 75 in place in its seat in the housing. Said block is provided with seats 20, 21 for the heads of threaded binding posts 22, 23 having nuts 24. 25 and 26 are conducting plates having threaded apertures 27 through which 80 contact screws 28, 29 are screwed.

Said screws 28, 29 are accessible through the holes 15, 16 respectively. The screw 30 has its head seated in a seat 31 in the block and extends through said block and through 85 the conductor 25 and a spacer sleeve 32, and through the laminated thermostatic contact spring 33 and the resilient spring-holder 34 which is secured in place by the nut 35 on the screw 30. The screw 30 with the sleeve 90 32 and nut 35 constitute the supporting post for the thermostatic spring 33. Said post is connected with the body 1 of the iron through insulating block 13, the housing 3 and the rearward extension 8 of such housing. 95

The resilient contact holder 34 is so constructed that its tip 36 contacts with the laminated contact spring 33 between said contact spring and the body of the iron, and tends to press the contact spring away from the body of the iron and toward the contact post 29; said laminated contact spring is 100 preferably provided with a platinum con-

tact point 37, and the contact screw 29 is preferably provided with a platinum contact point 38.

The floor 11 extends below the lower line 5 of the housing 3 and the resistance 2 has a terminal 40 adapted to be connected to the binding post 22; electrical connection 41 is secured to the binding post 23. The electrodes 42, 43 extend through the housing 10 3 and are insulated therefrom by insulation 44 in the usual manner and the electrodes 42 is connected with the resistance 2 by the resistance terminal 45. The block 13 is inserted into the case 10 and is secured 15 by the screw 19, then the smoothing iron is brought into position adjacent the block and housing and the terminal 40 is secured by the nut 24 of the binding post 22, and the electrical connection 41 leading from the 20 binding post 23 is secured to the electrode 43, then the housing 3 may be brought into position on the iron body and secured by the nuts 4, 5.

The temperature adjustment is made by 25 screwing or un-screwing the adjusting screw 28 and contact screw 29. If the adjustment proves to be such that the iron body 1 becomes over-heated before the contact between 37 and 38 is broken then contact screw 29 will be unscrewed.

The screw 29 is thus set at the factory at a predetermined heat deemed most satisfactory, and the adjustment by the housewife is preferably made by turning the 30 screw 28 when adjustment to her own purpose or desire is required.

When the screw 28 is screwed in, it acts upon the resilient contact holder 34 as a 40 lever to press the laminated spring 33 to produce a firmer contact between points 37 and 38. By releasing the screw 28 the laminated spring is allowed to respond more quickly to the heat radiated from the iron body 1.

45 The platinum or other lasting points of high fusibility and practically free from carbon are necessary to the success of the invention as it is important that the device shall not be easily put out of commission; 50 and without such points the arcing of the current at each make and break of the circuit will soon make the device inoperative.

It is also necessary that the contact points 55 be on the side of the thermo electric spring and that such spring shall be constructed and arranged to withdraw its contact point 37 from the fixed contact point 38 under the bending effect of heat radiated through 60 the insulating space between it and the smoothing iron body so as to avoid the difficulties hereinbefore pointed out.

In practice the extension 8 is ventilated by openings 46 at opposite sides thereof to allow air to pass freely to and from the cot-

tact-spring insulating chamber in said extension so as to insure against destructive heating the spring.

I claim:

1. An electric smoothing iron provided 70 with a housing secured to the iron body and constituting an extension beyond said body, and forming a space containing air; an insulating block mounted in the housing and spaced apart from the smoothing 75 iron body; and a thermostatic electrical cut out supported by said block and held thereby apart from the smoothing iron body so that the thermostatic element may be acted upon by the heat of the body without being 80 subjected to the high temperature thereof.

2. In an electric iron the combination 85 with a flat thermostatic electric contact spring having its sides practically parallel to an adjacent face of the body of the iron; of an insulating block; a housing provided with a chamber in which said block is seated; an adjustable contact point adapted to contact with the spring; and means to move said point to increase and decrease the tension on said spring.

3. In an electric iron the combination 100 with a thermostatic electric contact spring; of an insulating block; a housing provided with a chamber in which said block is seated; a contact screw provided with a contact point adapted to contact with the spring; means to support the contact spring; and a contact spring holder so constructed that its tip contacts with the contact spring and tends to press the contact spring toward the contact screw.

4. In a device of the character set forth, an adjustable contact post having its contact end provided with a contact point of 105 high fusibility; a supporting post connected to the body of the iron; a thermo electric contact spring supported by said supporting post; and said spring being provided with a contact point of high fusibility on 110 the side of the spring and arranged to normally contact with said contact point on said post.

5. The electric smoothing iron set forth, 115 comprising a body having an electrical resistance by which it is heated; a ventilated housing connected to said body, said housing extending rearwardly beyond said body and forming thereby an air chamber; an insulation block fixed to said housing at the rear 120 of said body with a space between said block and body; binding posts carried by said block, one being connected in an electrical circuit; a contact post carried by said block and electrically connected with the electrical resistance and provided with a platinum point; a thermo electric spring supported by said block and provided on its face opposite to said body with a platinum point, said spring adapted to bend under action of 125

heat to withdraw the platinum point thereof away from said contact post to break the circuit when the iron becomes over-heated; and means for applying tension to said 5 spring.

6. The electric smoothing iron set forth comprising a body having an electrical resistance by which it is heated; a ventilated housing fitted to and secured to the top of 10 said body and enclosing the electrical resistance thereof; an extension integral with said housing, said extension extending rearward of said body and enclosing a chamber and said extension having a rear wall with 15 a hole therethrough; an insulation block in the chamber of said extension, said block spaced away from said body and provided with a hole adapted to register with the hole in the rear wall of said extension; a screw bolt passing through the holes of the wall 20 and said block and adapted to secure the block to the wall; two conducting plates secured to said block on the side toward said body; a contact post inserted through said 25 block and screwed through said plate, said post adjustable away from or toward said body; a second contact point inserted through said block and screwed through the second conducting plate; a supporting 30 post extending through said block toward said body; a laminated thermo-electric contact spring mounted on said supporting post and extending to normally close the circuit through said contact post; a resilient spring 35 holder engaging said contact spring to normally press said contact spring toward said contact post; and means for adjusting said spring holder to increase or decrease its pressure on said contact spring.
- 40 7. The electric smoothing iron set forth comprising a body having an electrical resistance on the surface thereof by which it is heated; a housing fitted to and secured to the top of said body and enclosing the electrical resistance thereof; an extension integral with said housing, said extension ex-

tending rearward of said body and enclosing a chamber and said extension having a rear wall with holes therethrough; an insulation block in the chamber of said extension 50 said block spaced away from said body and provided with holes that are adapted to register with the holes through the rear wall of said extension; a screw bolt passing through a hole of the rear wall and block 55 for securing the block to the rear wall; two conducting plates spaced apart and secured to said block on the side opposite to the rear wall and toward said body; a fixed contact post inserted through said block and screwed through one of said plates; an adjustable contact post inserted through an opening in the rear wall of said extension and said block, and screwed through the other conducting plate; a contact point in the contact 60 end of said adjustable contact post; a supporting post secured to said block; a laminated contact thermo electric spring mounted on said supporting post, said spring arranged to extend through the space between 65 said block and body and positioned with its free end adjacent the contact end of said adjustable contact post; a second contact point mounted on said spring and arranged to normally engage the contact point on said 70 adjustable post; a spring holder carried by said supporting post and adapted to press the laminated spring toward said adjustable contact post; and an adjusting screw inserted through a hole in the rear wall of 75 said extension and through said block to regulate the pressure of said spring holder on said laminated spring, said adjustable post and adjusting screw accessible through the holes of the rear wall of said extension 80 for adjusting.

In testimony whereof, I have hereunto set my hand at Los Angeles, California, this 1st day of December, 1921.

LEROY R. BOWLES.

Witness:

JAMES R. TOWNSEND.
